UNITED STATES PATENT OFFICE

HANS CHRISTIAN HANSEN, OF FREDERIKSBERG, DENMARK, ASSIGNOR TO SOREN WISTOFT & CO.'S FABEKKER, AKTS., OF COPENHAGEN, DENMARK

RELEASING MECHANISM FOR AUTOMATIC VENDING MACHINES

Application filed February 14, 1929, Serial No. 339,986, and in Great Britain February 23, 1928.

This invention relates to a releasing device for automatic vending machines of the type capable of distinguishing between coins with and without a flange so that upon insertion of 5 a coin with a flange, for which such machine is intended, the opening member may be opened, whereas such opening cannot take place if a coin without a flange is inserted.

The releasing mechanism in question is essentially characterized by the combination of 10 a pair of coin feelers and a lever mechanism consisting of several levers coupled to a slide, one of the ends of one of the levers forming a bottom for a pocket for receiving a 15 coin inserted into the machine which, if it has a flange, is seized by the feelers and thereby causes the lever mechanism to be moved into such a manner as to allow an opening of the opening member of the machine, whereas if the coin is not flanged and is therefore not seized by the feelers, the lever 20 mechanism will lock itself if any attempt is made to open the said opening member and thereby prevent such opening.

25 In the accompanying drawings is shown a constructional form of such device, in which:

Figure 1 shows the device in side elevation, 30 Figure 2 the same seen from above, and

Figure 3 the same in sectional view along the lines I—I in Figure 1.

For sake of affording a greater simplicity some parts have been omitted in the Figures 2 and 3.

35 In the drawings the numeral 1 indicates a wall belonging to the machine casing. In this wall is journalled a horizontal shaft 2, Figures 1 and 3, on which there is fitted a swivelling bell crank 3, 4, the one arm 3 of which is normally horizontal or almost horizontal, and the outer end of this arm, in a manner not shown, thus coupled to the opening member of the respective machine that an opening 40 of the latter will cause a counter-clockwise rotation (Figure 1) of the bell crank 3, 4.

The other upwardly directed arm 4 of the latter is of a special shape. Its left-hand edge, Figure 1, forms a plane surface 5 obliquely inclined upwards to the left between

which and the plane upper surface of arm 3 there is a space 6 for receiving a roller 7 which will hereinafter be more particularly discussed, whereas the said edge of arm 4 forms a surface 8 coaxial with the shaft 2 (thus a circular-cylindrical surface) and thereafter a plane surface 9 which normally is in an almost vertical position. The upper edge of arm 4 forms, seen from the upper end of surface 9, first a plane surface 10, which normally is almost horizontal, thereupon a shoulder 11 which is parallel to the surface 10 and is at a greater distance than the same from the axis of the shaft 2 and from which a normally almost vertical surface 12 proceeds upwards and is continued by an oblique surface 13 extending upwardly and to the right, Figure 1, which surface 13 is again continued by a surface 14 (a circular-cylindrical surface) concentric with the shaft 2.

The arm 4 of the bell crank has, moreover, at the top at the side turned towards the wall 1, a comparatively short upwardly extending branch 15 which is closer to the wall mentioned than the remainder of the arm. The side of this branch turned from this wall, which normally is in an almost vertical plane, reaches down into a line with the hereinbefore mentioned surface 10. On the shank of a horizontal screw 16 screwed into the branch 15, there is revolvably fitted a roller 17, which is on the side of branch 15, turned away from the wall 1, and the axis of which is normally in, or almost in a vertical plane through the axis of shaft 2.

On the side of arm 4 of the bell crank 3, 4 turned away from the casing wall 1, an angularly shaped plate arm 19 is secured by screws 18 which close above the upper fixing screw 18 is bent over away from the arm 4 and then again upwards parallel to said arm. The upper edge of the plate arm 19 is coaxial to shaft 2.

The aforementioned roller 7 which normally is in the space 6, is revolvably fitted on the outer side of an arm 22 which itself is revolvably fitted to a pin 23 secured in the machine wall 1, and by the action of a spring 24, the one end of which is secured to the arm 22

while its other end is attached to a pin in wall 1, the roller 7 is normally held against the oblique plane surface 5 of the left-hand edge of bell crank arm 4, thereby ensuring a given position of the bell crank 3, 4 when the opening member of the machine is closed.

The machine wall 1 has at its top a flange 25, Figure 3, on which there is secured a top plate 26 having a longitudinal hole 21 which plate 26 has at its top a couple of longitudinal laths 27 to which there are secured by means of screws 28 a couple of plate strips 29 which together with the said laths 27 form guides for a slidable plate-shaped slide 30 which at its front (to the right in Figure 1) is bent upwards with a part 31. Its back (left side in Figures 1 and 2) forms a stop for a pair of feelers, more particularly discussed below, and into the middle of the part there is screwed a screw 33 which is held by a lock nut 32 and the head 34 of which forms the adjustable foremost limit for the hereinbefore mentioned coin pocket. The slide has close to its rearmost end (left end in Figure 2) a rectangular hole 300 and the other part of the slide has here a longitudinal hole 35 immediately over the longitudinal hole 21 in the top plate 26 which besides lies immediately below the said rectangular hole 300. On the top of slide 30 there is secured by means of a couple of screws 36 a reinforcing or wearing plate 37 which has a rectangular hole 38 of slightly smaller dimensions than the rectangular hole 300 in the slide 30, immediately over which is the hole 38.

Through the longitudinal hole 21 in the top plate 26, the hole 300 in the slide and the hole 38 in the plate 37 there is passed the uppermost part of an upwardly turned arm 39 of a bell crank 39, 40. The latter is rotatably fitted on a pin 41 fitted in wall 1, while its other arm 40, extending forwards (to the right in Figure 1) is bent and terminates in a downwardly turned nose 42 which normally bears against the hereinbefore mentioned roller 17, supported by the branch 15 of the arm 4 of the bell crank 3, 4. The nose 42 is under the action of a spring 43 held against the said roller, the one end of said spring being connected to arm 39 and the other end to a pin 44 fixed in the wall 1.

Upwardly through the longitudinal hole 21 in the top plate 26 and through the longitudinal hole 35 in the slide 30 there extends the upper end of a curved double-armed lever 45 swivelling on a shaft 46 secured in a suitable manner in wall 1. At its lower end the lever 45 has a roller 47 intended to co-operate with the circular cylindrical upper edge 20 of the angular plate arm 19 hereinafter more particularly discussed. Under the action of a spring 48, the one end of which is connected to a fixed pin 49, while its other end is connected to the upper arm of the lever 45,

the latter is held normally against the stop pin 490 fitted in wall 1.

To the upper side of slide 30 there is secured a part 50 having an E-section, i. e., an upright part with three horizontal plate-shaped flanges extending forwards, of which the lowermost is secured to the slide, while the end edges of the two others 51 and 52, Figure 1, form the rear limit of a pocket into which a coin will drop which is inserted into the machine. This pocket is limited at its sides by two plate arms 53, Figures 1 and 2, parallel to each other in the longitudinal direction of the slide standing on their narrow edge and extending horizontally and which each belong to a plate member which is in a suitable manner secured to the underside of the fixed top plate 26 and projects up through the longitudinal holes in the same and the slide, 21 and 35, respectively. At its front the said coin pocket is limited by the head 34 of screw 33 and the bottom of the pocket is formed by the upper end surface of lever 45.

54 are two plate-shaped feelers, one on each side of the said coin pocket, each of them being the one arm of a double-armed lever rotatable on a vertical pin 55 pointing upwards from the top plate 26, the other end 56 of which lever being at its outer end connected to a pin 58 likewise projecting upwards from the top plate 26. Each feeler has at its back on its inner edge (the edge turned towards the other feeler) a beak 59 while at its front on its inner edge there is formed a nose 60 which under action of the respective spring 57 on the feeler is held against the back (in Figure 2, left side) of the upwardly bent part 31 of the slide. Normally the two feeler beaks 59 opposite to each other, extending from opposite sides into the aforementioned coin pocket, each beneath the one plate arm 53, are at such a distance from each other that the flange of a coin for which the machine is intended will freely pass between them.

The operation of the arrangement is as follows:

Assuming that a coin of the proper denomination with a flange is inserted the coin passes through a coin chute (not shown) of the usual kind down into the aforementioned pocket so that it will rest on the upper end of lever 45. If now the opening member of the machine is operated for opening it, the bell crank 3, 4 is turned counter-clockwise (Figure 1) whereby the roller 17 is removed from the nose 42 of the bell crank 39, 40 and the consequence thereof is that the latter bell crank is turned clockwise under the action of the spring 43. Thereby the slide 30 is moved forwards (to the right in Figure 1) during which movement the flanges 51 and 52 of the part 50 on said slide will carry the coin with them, and as soon as the move-

ment of the slide commences and the forward upwardly bent part of the slide is thereby removed from the noses 60 of the feelers 54, the springs 57 will turn the feelers so that the two beaks 59 of the feelers are so far brought towards each other that the flange of the coin cannot pass between them. After only a short forward movement of the slide the flange is seized by the beaks of the feelers, these now bearing against the coin side surface closely within the flange and further forward movement of the slide is prevented.

The forward movement of the slide and the corresponding turning of the bell crank 39, 40 is not greater than that of the nose 42 of the bell crank during the opening of the opening member of the machine and the corresponding turning of bell crank 3, 4 strikes against the bevel 13 of arm 4. During the further turning of bell crank 3, 4 the bevel 13 will cause the bell crank 39, 40 to be turned back in a direction towards its normal position against the action of spring 43, while at the same time the slide 30 is moved back until this bell crank and with it the slide are again in their normal position at the moment when the circular-cylindrical surface 14 on arm 4 passes under the nose 42. The radius of surface 14 is, namely, equal to the distance between the axis of the shaft 2 and the upper horizontal tangential plane of roller 17 when the whole releasing mechanism is in a position of rest (normal position). At about the same time the plane surface 5 on the left edge of the arm 4 will leave the roller 7. During the further opening of the opening member of the machine and the consequent turning of the bell crank 3, 4 the slide 30 will thus remain in its normal position, the nose of the bell crank 39, 40 continuing to bear on the circular-cylindrical surface 14 while the roller 7 is held against the circular-cylindrical surface 8.

About immediately on the commencement of the said further opening the angular plate arm 19 meets the roller 47 below on the double-armed lever 45, and thereby turns this lever clockwise (Figure 1) until the circular-cylindrical upper edge 20 of the plate arm passes under the roller. The lever 45 has then moved into such a position, which it retains during the further opening operation, that the coin can fall down to the left of the upper end of lever 45 to be in any suitable manner conducted to a coin box or the like. The coin has namely previously been released by the feelers 54, viz., at the moment when the slide returned into its normal position, whereby the front upwardly bent part 31 of the slide by acting on the noses 60 turned the feelers in such a manner against the action of the springs 57 that the beaks are moved away from each other.

When the opening member of the machine is again closed, the bell crank 3, 4 is turned

in a direction opposite to that before mentioned. At the moment the surface 14 leaves the nose 42 of the bell crank 39, 40 this bell crank can turn a little under the action of spring 43 and thereby carry the slide forward. But by the action of roller 17 on the nose 60 the bell crank 39, 40 and with it the slide 30 is immediately after again moved into normal position. When the closing of the opening member is almost completed the surface 8 will leave the roller 7 and the latter and with it the arm 22 return into normal position. The double-armed lever 45 is by the action of spring 48 turned back into its normal position determined by the stop pin 490.

If, instead of a coin with flange, a coin without a flange (a wrong coin) is inserted into the machine and it is thereupon attempted to open the opening member, the bell crank 3, 4 will, as before, be turned counter-clockwise (Figure 1) so that the roller 17 will leave the nose 42 of the bell crank 39, 40. By action of the spring 43, the latter bell crank will be turned and thereby push the slide and with it the coin, forward. As the coin has no flange the feelers 54 will not stop the forward movement of the slide and the consequence thereof is that the bell crank 39, 40 is almost immediately turned so far that its nose 42 is caught by the shoulder 11 and the surface 12 on the arm 4 of the bell crank and the whole lever mechanism is then locked so as to prevent an opening of the machine. At the relatively great displacement of slide 30 corresponding to the comparatively great turning of bell crank 39, 40 the coin will be pushed so far forward that it will fall down to the right of bell crank 45 so as to be by any suitable means conducted out of the machine. The turn which the bell crank 3, 4 can perform under these circumstances is so small that the surface 5 of the arm 4 continues to be in contact with the roller 7, and when the opening member of the machine after the attempted opening is again released, the roller 7 will in consequence of the action of spring 34 on arm 22 cause the parts to return into normal position.

The details here shown and described may be varied in several ways without departing from the scope of the invention.

I claim:

1. Releasing mechanism for automatic vending machines, including a displaceable slide, a pocket in said slide for receiving an inserted coin, a pair of coin feelers for controlling the displacement of said slide, a detent for controlling the operation of the vending machine, mechanism including a plurality of levers, one of said levers being connected to said slide, a lug on said lever for cooperating with said detent, another of said levers forming the bottom of said coin receiving pocket, and means to cause the feelers to en-

gage and arrest a proper coin moving with said slide, the arrest of the movement of the slide and coin permitting the lever mechanism to be moved to effect operation of the machine, said feelers permitting free passage of an improper coin, said lever mechanism acting on introduction of an improper coin to prevent operation of the machine.

2. A releasing mechanism as claimed in claim 1, characterized in that said lever mechanism includes a bell crank coupled to the opening member of the machine, a spring actuated bell crank connected at one terminal to the slide and actuated in part by the first mentioned bell crank, said coin supporting lever being retained in normal position by spring means and adapted, during movement of the first mentioned bell crank, to be actuated to displace its upper end forming the bottom of the pocket whereby to permit the coin to fall at one side of the coin supporting lever, the movement of the slide and the second mentioned bell crank under the influence of the spring actuated means of the latter being arrested by engagement of the feelers with a proper coin, and said second mentioned bell crank being restored to initial position by the first mentioned bell crank during further movement of the latter whereby upon displacement of said coin supporting lever by the first mentioned bell crank the coin is permitted to fall.

3. A releasing mechanism as claimed in claim 1, characterized in that said lever mechanism includes a bell crank coupled to the opening member of the machine, a spring actuated bell crank connected at one terminal to the slide and actuated in part by the first mentioned bell crank, said coin supporting lever being retained in normal position by spring means and adapted, during movement of the first mentioned bell crank, to be actuated to displace its upper end forming the bottom of the pocket whereby to permit the coin to fall at one side of the coin supporting lever, the movement of the slide and the second mentioned bell crank under the influence of the spring actuated means of the latter being arrested by engagement of the feelers with a proper coin, and said second mentioned bell crank being restored to initial position by the first mentioned bell crank during further movement of the latter whereby upon displacement of said coin supporting lever by the first mentioned bell crank the coin is permitted to fall, said feelers being adapted to act upon insertion of an improper coin to permit free movement of the latter together with the slide and second mentioned bell crank to a position permitting the discharge of the improper coin, and means cooperating with the second mentioned bell crank in the last mentioned position of the latter to arrest the movement of the first men-

tioned bell crank and prevent completion of operation of the latter.

4. A releasing mechanism as claimed in claim 1, characterized in that the lever mechanism includes a bell crank coupled with the opening member of the machine, a second bell crank coupled with said slide, spring means normally acting upon the second bell crank and tending to displace the latter together with the slide, means on the first mentioned bell crank acting to normally retain the second bell crank in normal position and the spring means acting on the second bell crank to displace the latter upon initial movement of the first bell crank, said feelers being adapted to act to limit the movement of the slide and second mentioned bell crank under the influence of the spring means associated with the latter upon insertion of a proper coin and permitting displacement of the second mentioned bell crank to a greater extent upon insertion of an improper coin, means on the first mentioned bell crank acting to return the second mentioned bell crank to initial position when the movement of the proper coin and slide is arrested by said feelers.

5. A releasing mechanism as claimed in claim 1, characterized in that the lever mechanism includes a bell crank coupled with the opening member of the machine, a second bell crank coupled with said slide, spring means normally acting upon the second bell crank and tending to displace the latter together with the slide, means on the first mentioned bell crank acting to normally retain the second bell crank in normal position and the spring means acting on the second bell crank to displace the latter upon initial movement of the first bell crank, said feelers being adapted to act to limit the movement of the slide and second mentioned bell crank under the influence of the spring means associated with the latter upon insertion of a proper coin and permitting displacement of the second mentioned bell crank to a greater extent upon insertion of an improper coin, means on the first mentioned bell crank acting to return the second mentioned bell crank to initial position when the movement of the proper coin and slide is arrested by said feelers, and means on the first bell crank adapted to abut the second mentioned bell crank when the latter is displaced to the full extent of its movement upon insertion of an improper coin whereby to arrest and prevent completion of movement of the first mentioned bell crank.

6. A releasing mechanism as claimed in claim 1, characterized in that the lever mechanism includes a bell crank coupled with the opening member of the machine, a second bell crank coupled with said slide, spring means normally acting upon the second bell crank and tending to displace the latter together with the slide, means on the first mentioned

- bell crank acting to normally retain the second bell crank in normal position and the spring means acting on the second bell crank to displace the latter upon initial movement 5 of the first bell crank, said feelers being adapted to act to limit the movement of the slide and second mentioned bell crank under the influence of the spring means associated with the latter upon insertion of a proper coin 10 and permitting displacement of the second mentioned bell crank to a greater extent upon insertion of an improper coin, means on the first mentioned bell crank acting to return the second mentioned bell crank to initial position 15 when the movement of the proper coin and slide is arrested by said feelers, the first mentioned bell crank being adapted, upon restoration of the second mentioned bell crank to initial position to engage the coin supporting lever and to release a proper coin. 20
7. A releasing mechanism as claimed in claim 1, characterized in that said lever mechanism includes a bell crank coupled to the opening member of the machine, a spring actuated bell crank connected at one terminal to the slide and actuated in part by the first mentioned bell crank, said coin supporting lever being retained in normal position by spring means and adapted, during movement 25 of the first mentioned bell crank, to be actuated to displace its upper end forming the bottom of the pocket whereby to permit the coin to fall at one side of the coin-supporting lever, the movement of the slide and the second mentioned bell crank under the influence 30 of the spring actuated means of the latter being arrested by engagement of the feelers with a proper coin, and said second mentioned bell crank being restored to initial position 35 by the first mentioned bell crank during further movement of the latter whereby upon displacement of said coin supporting lever by the first mentioned bell crank the coin is permitted to fall, and means on said slide engaging the feelers and maintaining the latter in inoperative position prior to the initiation of operation of the machine and releasing the feelers and permitting the latter to engage a coin upon initial movement 40 of the slide. 45
8. A releasing mechanism as claimed in claim 1, characterized in that said lever mechanism includes a bell crank coupled to the opening member of the machine, a spring actuated bell crank connected at one terminal to the slide and actuated in part by the first mentioned bell crank, said coin supporting lever being retained in normal position by spring means and adapted, during movement 50 of the first mentioned bell crank, to be actuated to displace its upper end forming the bottom of the pocket whereby to permit the coin to fall at one side of the coin supporting lever, the movement of the slide and the second mentioned bell crank under the influence 55 of the spring actuated means of the latter being arrested by engagement of the feelers with a proper coin, and said second mentioned bell crank being restored to initial position 60 by the first mentioned bell crank during further movement of the latter whereby upon displacement of said coin supporting lever by the first mentioned bell crank the coin is permitted to fall, and means on said slide engaging the feelers and maintaining the latter in inoperative position prior to the initiation of operation of the machine and releasing the feelers and permitting the latter to engage a coin upon initial movement 65 of the slide. 70
9. A releasing mechanism as claimed in claim 1, characterized in that said lever mechanism includes a bell crank coupled to the opening member of the machine, a second bell crank actuated in part by the first bell crank connected with said slide and controlled by the feelers, said second bell crank, upon insertion of an improper coin, being adapted to move to a position obstructing movement of the first mentioned bell crank and preventing completion of operation of the latter. 75
10. A releasing mechanism as claimed in claim 1, characterized in that said lever mechanism includes a bell crank coupled to the opening member of the machine, a second bell crank actuated in part by the first bell crank connected with said slide and controlled by the feelers, said second bell crank, upon insertion of an improper coin, being adapted to move to a position obstructing movement of the first mentioned bell crank and preventing completion of operation of the latter. 80
11. A releasing mechanism as claimed in claim 1, characterized in that the lever mechanism includes a bell crank coupled with the opening member of the machine, a second bell crank coupled with said slide, spring means normally acting upon the second bell crank and tending to displace the latter together with the slide, means on the first mentioned bell crank acting to normally retain the second bell crank in normal position and the spring means acting on the second bell crank to displace the latter upon initial movement of the first bell crank, said feelers being adapted to act to limit the movement of the slide and second mentioned bell crank under the influence of the spring means associated with the latter upon insertion of a proper coin and permitting displacement of the second mentioned bell crank to a greater extent 85 90 95 100 105 110 115 120 125 130

upon insertion of an improper coin, means
on the first mentioned bell crank acting to re-
turn the second mentioned bell crank to ini-
tial position when the movement of the prop-
er coin and slide is arrested by said feelers,
5 a swivelling arm, spring means connecting
the swivelling arm to the first bell crank,
and means on said arm engaging a recess in
the bell crank, the portion of the latter adjac-
10 ent said recess having a surface coaxial with
the bell crank.

In testimony whereof I affix my signature.
